UNITED STATES PATENT OFFICE.

SAMUEL C. SCOTT, OF BROOKLYN, NEW YORK.

SLEEVE-BUTTON.

SPECIFICATION forming part of Letters Patent No. 314,613, dated March 31, 1885.

Application filed November 22, 1884. (No model.)

To all whom it may concern:

Be it known that I, SAMUEL C. SCOTT, a resident of Brooklyn, in the county of Kings and State of New York, have invented an Improvement in Sleeve-Buttons, of which the following is a full, clear, and exact description, reference being made to the accompanying drawings, in which—

Figure 1 is a side view of my improved sleeve-button, showing the shoe folded flat. Fig. 2 is a similar view of the same, showing the shoe folded together. Fig. 3 is a central section of the button as it is represented in Fig. 1, and Fig. 4 a central section of the same as represented in Fig. 2. Fig. 5 is a face view of the button, showing the shoe up. Fig. 6 is a face view of the same, showing the shoe down. Fig. 7 is a bottom view of the button as the same is represented in Fig. 1. Fig. 8 is a bottom view of the button as the same is represented in Fig. 2. Fig. 9 is a section on the line *c c*, Fig. 3. Fig. 10 is a vertical section on the line *k k*, Fig. 3. Fig. 11 is a vertical section on the line *c k*, Fig. 10. Fig. 12 is a sectional view of an old-style button.

This invention relates to an improvement on the button or stud which is described in Letters Patent No. 248,967, its object being to adapt the baser metals to the construction of a button of the kind described in said patent.

I find that in order to make a button like that described in said Letters Patent, hard solder is necessary for the attachment of the hinge-pieces to the lower ends of the two-part spring-post, and also for the attachment of said post to the head of the button. The necessity of using hard solder in such a case requires the button to be constructed of fine metal—such as gold—and precludes the manufacture of the same article out of base metal, such as brass. This is the fact, because the employment of hard solder requires so much heat as to take the temper out of the brass or analogous base substance, should it be endeavored to join brass by hard solder.

In Fig. 12 I have shown the hinge-pieces *a* to be attached to the ends of the two-part spring-post *B* by the line *b* of hard solder, and I also show the connection of the upper ends of this two-part spring-post with the head *A* of the button by the line *d* of hard solder. The con-

struction shown in Fig. 12 is, therefore, of use in manufacturing buttons of gold or precious metal, but not of use in manufacturing buttons of less precious metal.

My invention consists in a new form of spring-post, whereby I am enabled to connect the hinge-pieces thereto by soft solder, and whereby I am also enabled to join the head to the spring-post without the use of hard solder. It may here be well to state that hard solder and soft solder are well known by these terms to jewelers, soft solder requiring less heat but being less tenacious than hard solder. Yet I produce, through my improved construction of the parts, as strong if not a stronger connection with soft solder than could be produced by means of the hard-solder connection in following the construction shown in Patent No. 248,967.

Referring now to the drawings, so far as the same illustrate my improvement, the letter *D* represents the head of my improved button. *E E* is the two-part spring-post; *F F*, the two-part shoe. Each section of the spring post is constructed by being stamped up in a suitable die, so as to form at its lower end a plate or lip, *e*.

Fig. 10 shows one of the sections of the post in substantially face view. Fig. 11 is a cross-section of the same.

The hinge-pieces *f f* are put upon the lips *e e*, so as to be supported by them, and are joined thereto by soft solder, simply to be held in place, not to withstand any strain, for all the strain to which the hinge-pieces are subjected is taken up by the lips *e* and by the body of the post, not by the solder which joins the hinge-pieces to the post. When the hinge-pieces *f f* are thus secured on the lips *e e*, the shoe-section *F* is joined to the post by means of the pin *g*. The upper ends of the two sections *E E* of the spring-post are slipped through a sleeve, *h*, which is or may be attached to the lower side of a plate, *i*, which constitutes the inner portion of the head *D*. The upper ends of the sections *E E* of the spring-post pass through the sleeve *h*, and also through the plate *i*, and are bent apart on top of said plate *i*, as shown in Figs. 3 and 4. After this the covering-plate *D*, or head proper, is put on the plate *i*, as indicated. Thus the

spring-post is joined to the head without the necessary employment of solder. The sleeve *h* is of such length as may be necessary to give the two sections of the post the necessary 5 spring-action whenever the shoe of the button is folded or together.

The sleeve *h* may be attached to the plate *i* or may be a projection from the same substance as the plate *i*, or may be simply slipped 10 around the upper portion of the post.

I claim—

1. The post *E*, constructed with the horizontal lip *e*, and combined with the rigid

hinge-piece *f*, which rests on and is soldered to said lip, and with the pin *g*, shoe *F*, and 15 head *D*, substantially as herein shown and described.

2. A button constructed of the head *D*, plate *i*, sleeve *h*, two-part spring-post *E*, having lips *e*, hinge-pieces *f*, pins *g*, and two- 20 part shoe *F*, substantially as herein shown and described.

SAMUEL C. SCOTT.
